UNITED STATES PATENT OFFICE.

PERCIVAL VAN R. HARRIS AND JOHN D. REYNOLDS, OF PHILADELPHIA, PENNSYLVANIA.

RADIATOR GUARD.

Application filed March 5, 1921. Serial No. 449,814.

To all whom it may concern:

Be it known that we, PERCIVAL VAN R. HARRIS and JOHN D. REYNOLDS, citizens of the United States, residing in the city and county of Philadelphia, State of Pennsylvania, have invented a new and useful Radiator Guard, of which the following is a specification.

Our invention relates to a guard for a 10 radiator of an internal combustion engine, the same being of such construction that in the event of collisions or blows are imparted to said guard it will be enabled to endure the shock and strain to which it is subjected 15 without material injury or destruction, thus also preserving its protection for the radiator.

To this end, said guard consists of a frame and bars both of steel or iron the 20 sides of the former being of angular form in cross section, and the latter having its terminals seated on certain limbs of said frame, and the terminal portions resting flat against the other limbs thereof, the 25 relative portions of said bars being fused with the contacting limbs of the frame whereby the bars and frame are of integral construction and so jointless at their places of connection.

It consists further in a novel method involved in the manufacture of the guard.

The invention is satisfactorily illustrated in the accompanying drawing, but the important instrumentalities thereof may be 35 varied, and so it is to be understood that the invention is not limited to the specific details shown and described, as long as they are within the spirit or scope of the claims.

Figure 1 represents a perspective view of 40 a guard for an internal combustion engine embodying our invention.

Figure 2 represents a side elevation thereof.

Figure 3 represents a vertical section of a 45 portion on line 3-3 Figure 1.

Figure 4 represents a vertical section of the upper portion of the guard on an enlarged scale, on line 4-4 Figure 6.

Figure 5 represents a vertical section of 50 the lower portion of the guard on an enlarged scale on a line similar to line 4-4 Figure 6.

Figure 6 represents a vertical section of 55 the upper portion of the guard on line 6-6 Figure 4.

Figure 7 represents a front elevation of another form of the guard embodying the invention.

Similar numerals of reference indicate corresponding parts in the figures.

Referring to the drawings.

1 designates the frame of the guard, and 60 2 designates the bars or rods thereof which are preferably of a flat nature as shown. The frame is formed of an angular piece of 65 steel or iron composed of the limb or perimetrical member 3 and an inwardly directed flange 4 suitably bent into shape, one form of which is shown in Figure 1, the same producing a strong structure.

The bars in said figure extend vertically their upper terminals engaging the innerfaces of the perimetrical member 3 of the upper transverse or cross member of the frame and resting normally directly against 70 said faces. The backs of the adjacent portions of said upper terminals rest normally against the adjacent faces of the limb or flange 4 of said upper transverse or cross member of the frame.

The lower terminals of said bars engage the inner faces of the members 3 of the lower transverse or cross member of the frame and rest normally directly upon said faces. The backs of the adjacent portions 75 of said lower terminals rest normally against the adjacent faces of the limb of said lower transverse or cross member of the frame.

After the bars are placed in position on the frame, the terminals and adjacent portions of the former are welded electrically or by acetylene gas or other means to the upper and lower transverse or cross members of the perimetrical frame as at 5, whereby the contiguous portions of the bars 80 and cross members of the top and bottom of the frame respectively are fused, and so connected integrally and so the frame and the bars are an integral construction and comparatively jointless. The fusion or weld 85 is effected by directing the heat first along one face of each bar at the end, and then along the other face, producing two welds at each end of each bar.

Attention is directed to the fact that the 90 joints that primarily existed between the bars and contiguous members of the frame as illustrated by the dotted lines and arrows in Figure 3 disappear owing to the welding of said bars to said members as has been 100 110

stated, and so the integral and comparatively jointless construction of the guard is the result, the result of which is a light and inexpensive guard of a vastly strong nature, which, if subjected to the force or blows of a collision or otherwise will endure the shock to which it may be subjected without material fracture, disintegration or destruction.

In Figure 7, the frame is of elliptical form and the bars or rods 2 extend in horizontal direction and their terminals or terminal portions are welded to the side members of the frame with the result the same as in the other figures.

Having thus described our invention what we claim as new and desire to secure by Letters Patent, is:—

1. A radiator guard for motor vehicles embodying a perimetrical frame of angular cross-section, one limb of said angular cross section being disposed in a vertical plane and the other lateral thereto, and a series of bars disposed in edgewise relation within

said perimetrical frame, said bars having their ends secured to the lateral limb of the aforesaid frame and their adjacent edges free from connection with the vertical limb thereof.

2. A radiator guard for motor vehicles comprising an endless perimetrical frame of angular cross-section, said frame conforming in contour to the frontal outline of a radiator and having one limb disposed in a vertical plane and the other lateral thereto, and a series of parallel spaced flat bars disposed in edgewise relation within said perimetrical frame, said flat bars having their transverse end edges welded to the lateral limb of the aforesaid frame and their adjacent longitudinal edges free from connection with the vertical limb thereof.
